UNITED STATES PATENT OFFICE.

HARRY M. PFLAGER, OF ST. LOUIS, MISSOURI, ASSIGNOR TO TRANSOM DRAFT GEAR COMPANY, OF ST. LOUIS, MISSOURI, A CORPORATION OF DELAWARE.

DRAFT-GEAR FOR RAILROAD-CARS.

No. 911,264.

Specification of Letters Patent.

Patented Feb. 2, 1909.

Application filed June 17, 1908. Serial No. 438,984.

To all whom it may concern:

Be it known that I, HARRY M. PFLAGER, a citizen of the United States, residing at St. Louis, in the State of Missouri, have invented a new and useful Improvement in Draft-Gear for Railroad-Cars, of which the following is a specification.

My invention relates to that class of draft-gear which is applied directly to the body bolster without the use of draft-timbers and separate housing for the springs with their respective fastenings, and is in the nature of an improvement on the Letters Patent of the United States granted to me October 18, 1904, No. 772,370, for an improvement in draft-gear for railroad cars, having in view also the Letters Patent of the United States granted to me January 23, 1906, No. 810,805, in the same class; and my invention has for its object to simplify the construction and provide a strong, compact, and durable draft-gear.

The invention consists in eliminating the follower-plates, and the housings formed in the draw-bar and yoke for the springs as described in the said patent, respectively, combined with other features of novelty as hereinafter described and claimed, reference being had to the accompanying drawing forming part of this specification, whereon—

Figure 1, is a vertical transverse section through my improved draft-gear on line 1, 1, in Fig. 3, as applied to a metallic car body-bolster seen in front side elevation broken away; Fig. 2, a vertical transverse section through the draft-gear and a vertical longitudinal section through the corresponding part of the bolster on line 2, 2, in Fig. 3; Fig. 3, a top plan view of the bolster broken away and partly in horizontal section on line 3, 3, in Fig. 1, showing the draft-gear in top plan view; Fig. 4, a vertical longitudinal section through the draft-gear and a vertical transverse section through the bolster on line 4, 4, in Fig. 1, and Fig. 5, a detached front side elevation of the middle portion of the bolster as seen in Fig. 1, omitting the draft-gear.

Like letters and numerals of reference denote like parts in all the figures.

a represents the car body-bolster (broken away) which is preferably composed of cast steel integral throughout, and in the present case I-shaped in cross section except at its middle portion where the top and bottom

flanges 1, 1', on the front and rear sides of the web 2 are united to each other along their outer edges or thereabout, by an upright wall 3 which extends for a suitable distance on each side of the longitudinal center of the car, an opening or slot 4 being formed transversely through each wall 3 at, and for a suitable and equal distance from each lateral edge thereof, for the purpose hereinafter described.

The bolster a is perforated centrally for the king-bolt (not shown) and formed on its underside with the center-plate 5 in the usual manner, the top flanges 1 being united to the center-plate 5 by an upright, preferably square, tubular portion 6, which intersects the web 2 and surrounds the king-bolt, the middle portion of each wall 3 between the openings 4 being united to the tubular portion 6 preferably, by a lower strengthening rib 7.

b is the draw-bar extension (hereinafter termed the draw-bar) having at its inner end a head b' which is arranged transversely or T-wise thereto in the same horizontal plane therewith, the outer face 8 of the head b' being opposite to the front side of the bolster a and formed with a middle recess 9 which extends from the face 8 for a suitable distance along and vertically through the draw-bar b, the bifurcated portions of the head b' thus formed being adapted to straddle the middle portion, and to pass freely through the openings 4, of the front wall 3, and the face 8 of the bifurcated head b' being flush with the inner face of the said wall in the normal position of the draft-gear.

Transversely through the web 2 of the bolster a on each side of the tubular portion 6 and of the longitudinal center of the car, is formed an opening 10 corresponding to each opening 4 through the walls 3, and extending vertically from the top flanges 1 to a bottom web or bracket 11 which projects horizontally from the tubular portion 6 for a suitable distance along the web 2, and is adapted to form a bearing seat or support for the combined "draft" and "buffing" spring 12 which is placed thereon in parallel alignment to the said center, or longitudinally between the walls 3, the front end of each spring 12, in the normal position of the draft-gear, bearing against the inner side of the front wall 3 and the face 8 or inner end of the draw-bar b, b', while the rear end 110

of each spring 12 bears against the inner side of the rear wall 3 and the face 8' of a yoke *c* having a middle recess 9', and its bifurcated portions thereby formed arranged 5 and adapted to pass freely through the openings 4 in the rear wall 3 in a similar manner to that described for the inner end of the draw-bar *b*, *b'*, through the front wall 3, the arms 13 of the yoke *c* which are 10 adapted to straddle the springs 12 and pass freely through the openings 10 in the web 2 of the bolster *a*, being coupled at their free ends to the head *b'* of the draw-bar *b* by the pins 14 in the usual manner.

15 For insuring a bearing surface for the head *b'* of the draw-bar *b*, and for the yoke *c* through their respective openings 4 of the walls 3 in the operation of the draft-gear, each wall 3 is formed along the top and bottom edges respectively, of its openings 4, with an outwardly projecting horizontal flange 15, the flanges 15 of the front and rear walls 3 overlapping the head *b'* and the yoke *c* respectively at all times.

20 25 For assembling each spring 12 within the space therefor between the walls 3 of the bolster *a*, the outer end of each opening 10 through the web 2 on each side of the tubular portion 6, is preferably enlarged, or 30 made circular in form, diametrically somewhat larger than the spring 12 which can thereby be inserted therethrough and adjusted laterally on to its bearing seat 11 endwise to the walls 3, the springs 12 being prevented from lateral displacement on assembling the remaining parts of the draft-gear, on one side by the tubular portion 6, and on the other side by the arms 13 of the yoke *c*.

35 In operation, assuming the several parts 40 of the draft-gear to be in their normal position as described and shown by the drawing, on the front movement of the draw-bar *b*, *b'*, when "pulling," and consequent release of its face 8 from the front ends of the springs 45 12, the latter are compressed at their rear ends by the face 8' of the yoke *c* against the front wall 3 of the bolster *a*, while, on the rear movement of the draw-bar *b*, *b'*, when "buffing," and consequent release of the yoke 50 *c* from the rear ends of the springs 12, the latter are compressed at their front ends by the face 8 of the draw-bar *b*, *b'* against the rear wall 3 of the bolster *a*, whereby follower-plates, and housings for the springs 55 on the draw-bar and yoke, as described in

the said respective patents, are dispensed with, and the draft-gear thereby much simplified and rendered stronger, more compact, and durable.

I do not limit myself to the particular form and material of the bolster *a* described and shown on the drawings as the same arrangement of draft-gear is applicable to other forms of body-bolster by modifying its constructive details and utilizing a front 60 and rear member thereof, spaced apart and opposite to each other, to form the stops for the springs, said members being also adapted for the free play therethrough of the draw-bar and yoke of the draft-gear in the manner described at all times.

What I claim as my invention and desire to secure by Letters Patent is:—

1. In a car draft-gear of the character described, the combination with the under-frame having a front member and a rear member spaced apart from and opposite to the front member, of a spring element intermediate to and adapted to be compressed against each of the said members, a draw-bar adapted to engage the front end of the said element and slidably thereat through openings in the said front member, and a yoke coupled to the draw-bar and adapted to engage the rear end of the said element, and slidably thereat through openings in the said rear member, substantially as described.

2. In a car draft-gear of the character described, the combination with the body-bolster, of a front member, a rear member opposite to and spaced apart from the front member, springs arranged longitudinally between and adapted to bear endwise against the said members, suitable supports for the springs between the said members, a draw-bar adapted to engage the front ends of the springs and slidably thereat through openings in the said front member, and a yoke coupled to the draw-bar and slidably transversely through the bolster, the said yoke being adapted to engage the rear ends of the springs and slidably thereat through openings in the said rear member, substantially as described.

HARRY M. PFLAGER.
